(57) **CLAIM**

The ornamental design for a battery mounting case, as shown and described.

DESCRIPTIONFIG. 1 is an isometric view of a battery mounting case;
FIG. 2 is front view of the battery mounting case of FIG. 1;
FIG. 3 is a back view of the battery mounting case of FIG. 1;

FIG. 4 is a right side view of the battery mounting case of FIG. 1; and,

FIG. 5 is a top view of the battery mounting case of FIG. 1. The left side view is a mirror image of the right side view in FIG. 4.

The bottom view is a mirror image of the top view in FIG. 5.

The broken lines in the drawing indicate environmental structure and form no part of the design to be patented.
